UNITED STATES PATENT OFFICE.

MICHAEL C. MONAHAN, OF DIXON, ILLINOIS.

HUMIDIFIER.

1,232,954.

Specification of Letters Patent. Patented July 10, 1917.

Application filed November 2, 1916. Serial No. 129,246.

To all whom it may concern:

Be it known that I, MICHAEL C. MONAHAN, a citizen of the United States, residing at Dixon, in the county of Lee and State of Illinois, have invented certain new and useful Improvements in Humidifiers; and I do declare the following to be a full, clear, and exact description of the invention, such as will enable others skilled in the art to which it appertains to make and use the same.

This invention relates to new and useful improvements in humidifiers, and the primary object of the invention is to provide an air moistening apparatus that can be readily and easily attached to a steam radiator, and yet be controlled independently of the radiator.

Another object of this invention is to provide a humidifying apparatus consisting of an arrangement of pipes which may be easily secured to a steam radiator, and which comprises a perforated pipe disposed across the top of the radiator, whereby steam may be ejected into the room to bring the moisture therein to the recognized normal standard.

Still another object of this invention is to provide a humidifying apparatus for ejecting steam into a room, which is secured to a radiator, and which is so arranged that the water of condensation will be carried back to the radiator, but no steam will be returned therewith.

Another object of this invention is to provide a device of this character which is simple and durable in construction, inexpensive to manufacture, and one which will be very efficient in operation.

With these and numerous other objects in view, my invention consists of the novel features of construction, combination and arrangement of parts which will be herein referred to and more particularly pointed out in the specification and claim.

45 In the accompanying drawings:

Figure 1 is a side elevation of a steam radiator showing the attachment applied thereto;

Fig. 2 is a top plan view of the same;

Fig. 3 is a rear end elevation;

Fig. 4 is a front end elevation;

Fig. 5 is a section taken on the line 5—5 of Fig. 1; and

Fig. 6 is a detail sectional view of the check valve.

In the practical construction and applica-

tion of my invention any form or style of steam radiator can be used, and the form illustrated in the accompanying drawings shows my device applied to one type of 60 steam heating radiator.

The radiator 1 is of the conventional type, it being provided at one end which is called the inlet end 2, with a steam inlet 3 being provided with the usual type of cut-off valve 65 4. Extending along the top of the radiator 1, and projecting a short distance beyond the opposite ends of the same, is a perforated pipe 5 having spaced perforations 6 disposed longitudinally in spaced relation 70 along its upper surface.

The end of the perforated pipe 5 which projects past the inlet end 2 of the radiator, is connected therewith by a vertical inlet pipe 7, which is smaller than the perforated 75 pipe 5, and which has its upper end connected to the adjacent end of the perforated pipe, as shown at 8. The lower end of the steam inlet pipe 7 is connected as shown at 9 with the inlet end of the steam radiator 80 intermediate the ends of the end section thereof. This connection 9 is any ordinary type of tap found most suitable. The steam inlet pipe 7 is disposed at right angles to the perforated pipe 5, and to the tap at the 85 inlet end of the radiator, and the ends of the same are connected therewith by the ordinary type of L couplings.

Disposed intermediate the ends of the steam inlet pipe 7 is a cut off valve 10 which 90 is of any ordinary type, and which supplies means for regulating the flow of steam through this pipe from the radiator. By the operation of this valve, when the radiator is being operated, the flow of steam 95 through the pipe to the humidifier may be regulated at the will of the operator. Positioned above the cut off valve 10 on the steam inlet pipe 7 is a union connection 11 as clearly shown in Figs. 1 and 4 of the 100 drawing.

The opposite end of the perforated pipe 5 which projects from the other end of the radiator is provided with a condensation return pipe 12, by means of which the water 105 of condensation is returned to the steam heating system of the radiator. This pipe 12 is vertically disposed, and is positioned adjacent one side of the end of the radiator, and the upper end of the same is connected 110 by a short horizontally extending pipe 13 with the adjacent end of the perforated pipe

5. The connections between the adjacent ends of the above mentioned pipes are the conventional type of L couplings.

The lower end of the return pipe 12 is connected with the end of the radiator adjacent the bottom of the same through the medium of an additional short length pipe 14, that is horizontally disposed and is substantially parallel with the short length pipe 13, and 10 the same extends to a point substantially in the same vertical plane with the perforated pipe 5 disposed at the top of the radiator. The outer end of the short pipe 14 is turned inwardly at right angles thereto and is connected with the end of the radiator as shown at 15.

Positioned intermediate the ends of the short length pipe 14 is a check valve 16 that is provided with a vertically swinging flap 17 mounted on a horizontal pivot 18, and which provides means whereby the steam will be prevented from returning from the radiator to the humidifier through the pipe 12, although the water of condensation 20 may pass therethrough. The object of offsetting the return pipe 12 at one side of the end of the radiator, by means of the short pipes 13 and 14, is to provide a space for the valve 16 which includes a flap 25 mounted on a horizontal pivot, this having been found most practical in the use of this device. The connections between the ends of the short length pipe 14, the adjacent end of the return pipe 12, and the end of the 30 radiator are the conventional type of L couplings commonly used.

By experiment it has been demonstrated that the moisture in rooms heated by radiators employing the steam system is far below 40 the recognized normal standard, which condition is productive of much discomfort and is also detrimental to health. When the proper amount of moisture is supplied to a room heated by steam radiators, a much lower temperature can be maintained without discomfort to the occupants. By the attachment of my form of humidifier to any type of steam radiator, the ejection of live steam into the room will raise the moisture 45 to the desired density. The amount of steam may be regulated, and when the moisture in the room reaches the desired normal standard, the flow of steam may be cut off.

This humidifier consists only of the system of pipes, that are positioned on any 55 type of steam radiator, and the same may be easily and simply applied thereto. When in position, the steam passes from the radiator up through the vertical inlet pipe to the perforated outlet pipe which is disposed 60 along the top of the radiator, where the same is fed into the room through the perforations in this pipe. The water that condenses flows to the other end of the pipe, and through the return pipe 12 back into the 65 steam heating system at the opposite end of the radiator. The return pipe 12 is offset, and the lower horizontally extending offset short pipe of the same is provided with a check valve which has a valve flap mounted 70 on a horizontal pivot, whereby the steam will be prevented from returning from the radiator to the humidifier, but the water of condensation may readily pass therethrough.

From the foregoing description of the 75 construction and operation of my improved humidifier, the manner of applying the same to use, and the operation thereof will be readily understood, and it will be seen that I have provided a simple and efficient device 80 of this character for carrying out the object of the invention.

I claim:

A humidifier comprising a perforated pipe to be disposed above a steam radiator, 85 a steam inlet pipe connecting one end of said perforated pipe with the inlet end of the radiator, a cut-off valve in said inlet pipe, a condensation return pipe having one end connected to the other end of said perforated pipe, a short horizontal pipe connecting the lower end of said return pipe to the end of said radiator, a check valve in said horizontal pipe whereby condensation will be permitted to return to the radiator, 90 and steam in said radiator will be prevented from passing to the perforated pipe through said return pipe.

In testimony whereof I have hereunto set my hand in the presence of two subscribing 100 witnesses.

MICHAEL C. MONAHAN.
